UNITED STATES PATENT OFFICE.

JOHN W. BEALL, OF CHICAGO, ILLINOIS.

SECURER FOR GATES AND DOORS.

No. 823,501.

Specification of Letters Patent.

Patented June 19, 1906.

Application filed March 19, 1906. Serial No. 306,882.

To all whom it may concern:

Be it known that I, JOHN W. BEALL, a citizen of the United States of America, and a resident of Chicago, county of Cook, and State of Illinois, have invented certain new and useful Improvements in Securers for Gates and Doors, of which the following is a specification.

The main objects of this invention are to provide an improved form of prop for securing a fence-gate in a partly-opened position and to provide a device of this class which may be readily attached to either wooden or wire fence gates without requiring special construction for each. I accomplish these objects by the device shown in the accompanying drawings, in which—

Figure 1 is a front elevation of a gate provided with a prop constructed according to this invention. Fig. 2 is an enlarged front view in perspective of the hinge member which connects the prop to the gate. Fig. 3 is a rear view of the same, also in perspective, and illustrating the method of applying the same to a wire structure such as is used in the gates of wire fences.

In the construction shown the prop 1 is of wood and is connected at its upper end to a hinge-plate 2. The plate 2 has a pair of forwardly-extending ears 3, which are pivotally connected by the pin 6 with corresponding ears 4 on the bracket-plate 5, which secures the brace to the gate. The plate 2 is provided with holes 7 to receive bolts for fastening said plate to the brace 1. The rear face of the plate 2 has a rearwardly-extending lug 8 near the hinge-joint, adapted to engage the end of the brace 1, and has also two lugs 9 near its lower end adapted to engage opposite sides of the brace 1. These lugs insure a rigid connection between the plate 2 and the brace 1 and take up the strain of the brace, so as to prevent the screws or bolts in the holes 7 from becoming loosened.

The plate 5 is provided with a plurality of bolt-holes 10 and 11. The plate 5 has connected therewith a spring-clip 12, provided with a pair of forwardly-extending arms 13, which are adapted to engage the sides of the brace 1 and hold the same in a lifted position. The plate 5 has on its rear face a pair of rearwardly and downwardly extending hooks 14. The upper surface of said hooks forms a shoulder for engaging the lower edge 15 of one of the cross-bars 16 of a wooden gate. Bolts passing through the apertures 10 se-

cure the plate 5 rigidly against the cross-bar 16 and assist the shoulders 14 in resisting the thrust of the brace 1. The lower bolt-hole 11 is located below the hooked shoulders 14 and is intended for use only when the device is applied to a wire fence, as shown in Fig. 3. The rear face of the plate 5 is also provided with a plurality of lugs or ridges 17 and 18. These are all of the same height and of less height than the hooks 14. When the device is applied to a wooden fence, as in Figs. 1 and 2, these lugs bear upon the face of the cross-piece 16 and serve to space the plate 5 slightly away from said cross-piece, but at the same time give the same a firm bearing. This air-space is of advantage, since it prevents the accumulation of moisture under the plate 5, and thus prevents decay of the cross-piece 16.

The lugs 18 are located in pairs, respectively, at opposite sides of each of the bolt-holes 10 and 11. They are spaced away from each bolt-hole a distance which corresponds to the usual thickness of wire ordinarily used in the construction of wire fences. The height of the lugs 18 also corresponds to such thickness. The vertical "stay-wire" of a wire-fence gate is shown at 19 in Fig. 3, and one of the horizontal "strand-wires" is shown at 20. These wires are connected by any usual form of joint to prevent relative slipping. When the plate 5 is secured to a wire-fence gate, the hooks 14 are passed over one of the horizontal wires 20 and the vertical wire is placed between the lugs 18. Bolts are then passed through the holes 10 and 11 at either side of the stay-wire 19, and said wire is confined between the bolt and the adjacent lug 18 by means of the nut and washer 21 on the bolt. The lowest hole 11 is located immediately below the hooks 14, so that when a bolt is passed through said hole for engaging the stay-wire 19 it will at the same time bear against the horizontal cross-wire 20 and prevent the plate 5 from slipping upwardly on the stay-wire 19. The lugs 17 are of the same height as the lugs 18 and are located near the outer edges of the plate 5, so as to provide a firm bearing for the same when it is applied to a wooden fence, as in Figs. 1 and 2.

The operation of the device shown is as follows: The prop 7 is lifted, as indicated by the dotted lines in Fig. 1, when not in use, being held in such position by the spring-clip 12. When it is desired to secure the gate in a partly-open position, as for causing animals

to pass through the gate one at a time, the brace 1 is dropped to an inclined position with its end resting upon the ground, as in Fig. 1. The application of the device to both 5 wooden and wire fence gates will be readily understood from the foregoing description.

What I claim as my invention, and desire to secure by Letters Patent, is—

1. A gate-securer comprising a plate, a 10 brace hinged to said plate on a horizontal axis, a spring-clip mounted on said plate and adapted to retain the brace in a lifted position, and a shoulder on the under side of said plate and adapted to engage the lower edge 15 of a cross-bar on the gate for resisting the upward thrust of the brace when the same is in a downwardly-inclined position.

2. A gate-securer comprising a plate provided with means for securing the same to a 20 cross-bar of a gate, a second plate hinged to the first and having on one face an end lug and a pair of side lugs, a brace secured to the said second plate and fitting between said side lugs and having a shoulder bearing 25 against said end lug, and said first plate having thereon a lug adapted for engaging the lower edge of said cross-bar.

3. A gate-securer comprising a plate and a 30 brace pivotally mounted on said plate, said plate having therethrough an aperture adapted to receive a bolt for securing the plate to the gate, lugs on the rear face of said plate at opposite sides of said aperture and spaced apart to permit a wire to be passed between the bolt and one of said lugs, shoulders on the 35 rear face of said plate adapted to engage a horizontal wire for supporting the plate, and a bolt-hole located between said shoulders

and the lower end of the plate for receiving a bolt adapted to prevent the wire from shifting out of engagement with said shoulder.

4. A gate-securer comprising a plate provided with bolt-holes for securing the same to a gate, a brace hinged to said plate and adapted to depend therefrom in an inclined position for propping the gate, a rearwardly-extending shoulder near the lower part of said plate having its upper face adapted for engaging the lower edge of a cross-bar as in a wooden gate and having its lower face in the 50 form of a hook and adapted to engage a horizontal wire as in a wire-fence gate, said plate having on its rear face lugs located at opposite sides of said bolt-holes and spaced therefrom and adapted to confine a vertically-extending wire between said lugs and the bolts, bolts arranged to bear across said lugs for securing said plate against such vertical wire, and said plate having also a bolt-hole and lugs located below the hooked face of said 55 shoulder, substantially as described.

5. A gate-securer comprising a plate, having on one face a bearing-surface adapted to fit against a flat surface, a brace hinged at one end to said plate, bolt-holes in said plate, 60 bolts extending through said holes, the face of said plate being depressed from the bearing-surface at the sides of said bolt-holes to permit a wire to be confined between the plate and bolts in the manner described.

Signed at Chicago this 14th day of March, 70
1906.

JOHN W. BEALL.
